[57] CLAIM

The ornamental design for a radio receiver, substantially as shown and described.

DESCRIPTION

FIG. 1 is a perspective view of a radio receiver showing my new design;

FIG. 2 is an elevational view of the end shown on the left in FIG. 1;

FIG. 3 is an elevational view of the end shown on the right in FIG. 1;

FIG. 4 is a side elevational view, with the receiver shown as broken away for convenience of illustration;

FIG. 5 is a top plan view thereof;

FIG. 6 is a partial perspective view of the FIG. 2 end of the receiver; and

FIG. 7 is a partial perspective view of the FIG. 3 end of the receiver.

FIG. 1

FIG. 2
